UNITED STATES PATENT OFFICE.

JAMES P. O'BRIEN, OF NEW YORK, N. Y.

SIGN.

SPECIFICATION forming part of Letters Patent No. 360,900, dated April 12, 1887.

Application filed November 4, 1886. Serial No. 218,013. (No model.)

To all whom it may concern:

Be it known that I, JAMES P. O'BRIEN, a citizen of the United States, residing at New York, in the county of New York and State of New York, have invented a new and useful Improvement in Signs, of which the following is a specification.

This invention relates to improvements in advertising-signs; and it consists of the peculiar combination of devices and in the novel construction and arrangement of the various parts for service, substantially as hereinafter fully described, and particularly pointed out in the claims.

15 The primary object of my invention is to provide an improved advertising-sign of novel and simple construction, which shall attract the attention of passengers in railroad-cars and vehicles of any description, the customers in 2c stores, passers on streets, &c.

Heretofore it has been proposed to provide an advertising-sign with one or a series of openings, and to suspend or pivot in each opening a movable plate or disk which is free to vibrate or move therein under the action of 25 the wind on the sign, and also when a jarring or other movement is imparted to the sign; and it has also been proposed to connect the sign to an electro-magnet, so that all of the series of 3c disks in the sign will be moved simultaneously by the vibration of the sign. These devices are somewhat expensive and difficult of manufacture, and hence they do not meet the demands of all advertisers.

35 In my improved sign I propose to provide a piece or back, which is usually arranged in rear of the sign proper, and carries the spots, disks, or other devices, and is loosely suspended by suitable means, so that all of the 40 disks or spots appear to move together. The disks on the vibrating piece or back can be seen or observed through the openings in the sign proper, and the back or piece is caused to vibrate or move while the sign proper re- 45 mains stationary, and thus secure the attractive and desirable feature in a sign of the class to which my invention relates at a very small cost.

In the accompanying drawings, which illustrate a sign embodying my improvements, Figure 1 is a front elevation. Fig. 2 is a vertical transverse sectional view thereof, and

Fig. 3 is a front elevation with the sign proper removed to show the manner of suspending the sign-back more clearly. Fig. 4 is a front 55 elevation of a modified form of my invention.

Referring to the drawings, in which like letters of reference denote corresponding parts in all the figures, A designates the sign proper, which has the usual word or words printed, 6c painted, stamped, or otherwise impressed thereon. Each word, letter, or character of the sign has a series of transverse openings, a, formed therein, as is usual in signs of this class; or the entire letter may be cut out. 65

B designates the vibrating piece or back, which is arranged in rear of the sign proper, and this piece or back has a series of spots or disks, b, thereon, which are arranged so that they can be observed through the openings a 7c in the sign A. These disks can be made separately from the vibrating piece or back and suitably secured or affixed thereto. The spots or disks can be printed, stamped, painted, or otherwise impressed thereon. The spots or 75 disks are arranged to form the word, letter, or character in outline of the part through which the spots or disks can be seen—as, for instance, in the case of the sign here shown, the word "Eden" is formed on the back in outline by a series of disks, which are suitably arranged to form the letters of which the word is composed, as will be very readily understood. 80

The sign proper, A, is preferably secured or 85 affixed in a frame, C, in any suitable or preferred manner, and this frame is to be rigidly held in place in a car or other vehicle, a store, or other place where it can be observed by passers, although the sign can be fixed in any 90 other suitable manner. I have shown it fixed in the frame C merely for the purpose of illustrating the manner of holding and protecting the sign in a street-railway car; but it is obvious that the sign can be fixed directly to the 95 car, and without the frame, or to any other place.

The vibrating piece or back is loosely suspended in rear of the sign by resilient devices which give or impart the vibrating motion 100 to the same when the slightest shock or jar is imparted to the device—as, for instance, when the car to which the sign is affixed is in motion. These resilient suspending devices pref-

ures such as I employ. Further than this, the letters on the flexible sheet of glass being visible solely by reason of the stationary sheet, it necessarily follows that the letters would 5 show very dimly, and the variegated or changing appearance of the letters would not be plainly visible, especially since the glass sheets are colored. In my device these objections are overcome and the advantages heretofore 10 pointed out are attained to the highest degree.

Having thus fully described my invention, what I claim as new, and desire to secure by Letters Patent, is—

1. In a sign, the front or sign proper, constructed of some opaque material and having the words, letters, characters, or figures thereon, and the transverse openings cut through the sign-front at the point where the words, characters, or figures are arranged, combined 15 with a vibrating piece having a plain ground with spots, disks, or other figures thereon, which spots, disks, or figures correspond in shape and size to the openings cut out of the
2. In a sign, the front or sign proper, having the opaque figures thereon, and the openings cut through the sign-front at the points where the figures are arranged, which openings are either at the eyes, mouth, or at any point of 20 the figure, as explained, combined with the vibrating piece or back having spots or disks or figures thereon, which spots or disks or figures correspond with that portion of the figure on the sign-board through which the 25 openings are cut, and said spots, disks, or figures being seen only through the said openings, as set forth.

In testimony that I claim the foregoing as my own I have hereto affixed my signature in 30 presence of two witnesses.

JAMES P. O'BRIEN.
